STENCILING APPARATUS

Frederick B. McQuiston, Crafton, and Ernest M. Hommel, Pittsburgh, Pa., assignors to The O. Hommel Company, a corporation of Pennsylvania

Application July 9, 1936, Serial No. 89,742

14 Claims. (Cl. 101—125)

Our invention relates to stenciling apparatus, and consists in improvements and refinements of the apparatus described in our co-pending application for Letters Patent Serial No. 41,904, filed September 24, 1935, now Patent No. 2,054,435, dated September 15, 1936.

As mentioned in said patent, we are concerned with the surface ornamentation of tumblers, bottles, jars, and other objects of circular cross section, and our apparatus is particularly, although not exclusively, intended for use in applying characters or designed decorations of vitreous color material upon such objects of glass, to the end that the objects may be fired and in known manner the color material vitrified and fused in the surface of the glass.

The apparatus includes a flexible stencil sheet, impervious in main and pervious in pattern, drawn taut and supported an interval above and in parallelism with a surface that bears a coating or film of decorating material. The object to be decorated is rolled across the upper face of the stencil, and, under the pressure of the object, the flexible stencil is caused to yield from the plane of its expanse downward, and into contact with the film-bearing surface beneath. The decorating material is exuded through so much of the stencil as is pervious and upon the surface of the rolling object.

As already mentioned, the invention consists in refinements and elaborations, and, upon remarking that our improved apparatus embodies features which will prove valuable in decorating round objects of various sorts, we shall describe an embodiment of the invention in apparatus for decorating drinking glasses or tumblers whose circular side walls taper from top to bottom.

In the accompanying drawings Fig. I is a view in side elevation of the apparatus, with a particular cam element appearing in vertical section; Fig. II is a view of the apparatus in plan from above; Fig. III is a diagrammatic view, showing particular elements of the apparatus to larger scale and on the planes indicated at III—III in Fig. I; and Fig. IV is a view in side elevation and to still larger scale of one of the object-supporting devices of the apparatus.

Referring to the drawings, our apparatus includes an endless band 1, trained over four rollers 2, 3, 4, and 5. In this case, the band extends between the rollers 2 and 3 horizontally, and is supported and reinforced from beneath, by means of a rigidly mounted platen 6, cf. Fig. III. And above the upper, horizontal reach of the band, a

flexible stencil sheet 7 is supported on the frame or bed B of the machine.

The structure of the stencil sheet is fully described in Letters Patent No. 2,011,383, granted to Ernest M. Hommel on August 13, 1935, and suffice it herein to say: first, the sheet is impervious in main and pervious in the pattern of the characters or decoration to be applied to the drinking glasses (Fig. II shows the stencil provided with an open-work pattern P); second, the flexible stencil is drawn taut and secured to a frame 8; and third, the frame 8 supports the stencil in parallelism with and an interval above the area of the band 1 lying upon the platen 6. A film of decorating material is automatically applied to the outer surface of the band 1, and the band is advanced intermittently to carry the applied film into position beneath the open-work pattern of the stencil.

The glass objects G to be decorated are successively brought to bear upon the upper face of the stencil sheet, and rolled across the open-work pattern P provided therein. Under the pressure of each rolling object, the stencil sheet is caused to yield downward from the normal plane (7a, Fig. III) of its expanse and into contact with the film-bearing surface of the band beneath. The line of contact of the stencil with the band advances with the rolling object, and the decorating material is squeezed through the open-work pattern P, and is progressively applied to the surface of the object. There is no slipping between the surface of the object and the stencil, nor smearing of the decorating material over the upper face of the stencil; the rolling object, upon traversing the pattern area of the stencil, is provided with a decoration in the clean outline of the pattern P.

The machine includes a work-carrier which consists in a turn-table 9 secured to the upper end of a vertical shaft 10, and carrying a plurality of work-supporting devices 45. In this case two of such devices are provided.

The shaft 10 is trunnioned in a sliding head 12 secured, by bolts 12a, upon the bed B of the machine, and a bevel-gear 11 is secured to the lower, projecting end of the shaft, as shown in Fig. I. A bevel-pinion 11a, meshing with gear 11, is feathered upon a horizontal counter-shaft 28, and an electric motor 13 is arranged to drive the counter-shaft at suitable speed through a gearbox 26. Thus, the turn-table is rotated, and the glass objects introduced to supporting devices 45 are moved through a circular path a, as illustrated in Fig. II.

As already mentioned, the objects to be decorated in this case are drinking glasses or tumblers whose side walls taper from top to bottom, and it will be understood that each tumbler **G** 5 comprises the frustum of a cone. In accordance with our invention, the work-carrier **9**, **45** is adjustable relatively to the stencil sheet **7**, in such manner that the center of the circular path **a** through which the tumblers **G** are moved, that 10 is, the axis of shaft **10**, as viewed in plan from above the machine, is caused to register precisely with the apex of the cone of which the object comprises a frustum. (The broken lines **c** in Fig. II are illustrative of the cone of which 15 tumbler **G** is a frustum.) Thus, each tumbler advancing through the circular path **a** rolls on its side over the face of the stencil sheet **7**, and the line of contact of the tumbler with the stencil extends radially of shaft **10**. As the tumbler 20 so rolls, the line of contact between tumbler and stencil moves angularly about the axis of such shaft as a center, whereby the rolling engagement between the stencil sheet and the tumbler is a perfect rolling engagement at all points 25 longitudinally of such line of contact.

In effecting the adjustment of the work-carrier **9**, **45** relatively to the stencil, the bolts **12a** are loosened, and the head **12** is slid longitudinally of the supporting bed **B**, the bolts **12a** moving 30 along slots **12b** that are provided in known way in the bed. A stirrup **27** (Fig. I), engaging the shaft **10** with running fit, extends downward and embraces the bevel-pinion **11a** splined to counter-shaft **28**, and, by virtue of such means, the 35 bevel-pinion is caused to slide longitudinally of the counter-shaft, and to remain in mesh with the gear **11**, during the adjustment of the work-carrier upon the bed **B**. When the work-carrier is properly adjusted, with the axis of shaft **10** in 40 registry with the apex of the cone **c** of the tumblers to be decorated, the bolts **12a** are tightened. The work-carrier is ready for immediate service, without the necessity of adjusting gears and other driving connections.

45 Each object-supporting device **45** includes an arm **14** extending radially of the turn-table **9**, and pivotally connected thereto, by means of a pin **15a** secured in a bracket **15** which is integrated with the table. The distal end of the arm 50 carries an inverted yoke **75**, in which the tumblers are immediately engaged, and a branch **96** extends upward and outward from the arm and provides support for a roller **17**. The arm **14** extends through a vertically reciprocable stirrup **46** 55 which, by means of a spring **47**, tends to sustain the arm with its distal end raised, in the position indicated at the right of Fig. I, and with the stirrup held by spring tension against the nether face of a rigid lug **49** projecting from bracket **15**. 60 Referring particularly to Figs. III and IV, the yoke **75** includes a basal bar **18**, and two legs **18a** and **18b**. The bar **18** extends between two parallel plates **50** which are secured to the end of arm **14**, and interconnected by means of rigid cross-members **51**; between the plates **50** a fulcrum element **52**, backed by a spring **53**, bears upon the medial portion of bar **18** from above; a pair of headed stems **54**, rigid with the bar, extend upward between plates **50** and severally through 65 slots **55** in cross-members **51**; and a compression spring **56** is arranged on each stem, bearing against the cross-members **51** from below and severally urging the heads of the stems against the cross-members from above. Thus, the basal bar of the yoke **75**, as so supported between the

75 plates **50**, is movable angularly within a small range about the fulcrum element **52**, and is movable vertically against the tension of spring **53**. And in either of such permissive movements, it will be observed that the plates **50** serve to maintain the bar **18** (as viewed in plan from above) in alignment with the arm **14** that extends radially of the turn-table **9**.

The leg **18a** of the yoke **75** is rigidly secured in adjusted position on the basal bar **18**, while the opposite leg **18b** is adapted to swing, on a pivot **20**, about such basal bar. A conical block **21** is mounted on a rotary spindle **22** carried by the foot of leg **18b**, and anti-friction bearings may be employed in the known way, to insure that the block shall be delicately sensitive to rotative stress. And in like manner a rotary knob **24** is secured in the foot of leg **18a**. The tumbler to be decorated is seated upon the conical block **21**, as shown at **G** in Fig. IV, and a pair of springs **25**, effective between the basal bar of the yoke and the leg **18b**, tends to swing such leg counter-clockwise, with the consequence and effect that the bottom of the mounted tumbler **G** is held against the rotary knob **24**. The axes of knob **24** 20 and block **21** extend in alignment and parallel to the arm **14**, and, manifestly, when the arm in the course of its rotation crosses the stencil sheet **7**, the supported tumbler rolls freely over the face of the stencil in the manner already described. In introducing a tumbler to the apparatus, the attendant swings the leg **18b** upward into work-receiving position, as shown in broken lines in Fig. IV, the springs **25** at first resisting and ultimately aiding rotation about pivot **20**. 25 In such work-receiving position of the leg **18b**, the attendant readily slips the tumbler to be decorated into position upon the conical block **21**. The leg **18b** is then swung back into its normal position, and the tumbler is by springs **25** held 30 in the position shown in Fig. IV, ready to be carried across the face of the stencil. It may be remarked that a plurality of rubber strips **21a** are embodied in the block **21**, with the presented edges of the strips lying an interval outward from 35 the face of the block. These strips, rather than the side face of the block, engage the inner surface of the installed tumbler, and, accordingly, the wall of the tumbler is engaged on lines, rather than on an extended area, of contact. In this 40 way, the objectionable tendency for the tumbler to become too tightly wedged upon the conical block is eliminated.

45 In service the attendant stands in the station **A**, indicated in Fig. II, and, as each of the continuously rotating arms **14** advances from a position above the stencil sheet towards him, he removes the decorated tumbler and introduces in its place a tumbler to be decorated. An arcuate cam-rail **16** is mounted above the stencil sheet **7**; 50 two rigid posts **19** and arms **23** afford the mounting, and the posts are horizontally adjustable on the bed **B** of the machine, while the arms **23** are vertically adjustable on the posts. Each work-supporting device carries the installed tumbler **G** 55 clockwise in the circular path **a**, from the station **A** to a position above the stencil sheet, and during such advance the stirrup **46** (under the urging of spring **47**) yieldingly sustains the arm **14** in such position that the tumbler is supported an interval **i** (Fig. I) above the face of the stencil sheet. As the supported tumbler moving through path **a** approaches a position above the stencil sheet, the roller **17** enters engagement with a 60 downwardly curved portion **16a** of the cam-rail. 65 70 75 80 85 90 95 98 99 100

Thereupon, the work-supporting device is positively swung downward, about pin 15a as center, and against the resistance of stirrup spring 47; and the tumbler borne by the device engages 5 and depresses the stencil sheet 7, and moves it into contact with the film-bearing band 1, as will be understood upon considering Fig. III. Thus, while rotation of the work-supporting device continues unabated, the tumbler is rolled across the 10 surface of the film-bearing band 1, with the stencil sheet interposed between. In such manner a decoration of color material is applied in desired pattern. By virtue of the yielding and fulcrumed mounting of the tumbler-supported 15 yoke 75 at the end of arm 14, the advancing tumbler, moved positively downward by the cam-rail 16, adjusts itself to the face of the stencil, to make accommodation for any inaccuracy in the 20 adjustment of the machine, and, during the rolling advance of the tumbler across the stencil sheet, the springs 53, 54 yield, to compensate for such irregularities as may exist in the surface of the tumbler.

When the rolling tumbler has traversed the 25 pervious area of the stencil, the roller 17 moves under the influence of the spring-backed stirrup 46 (Fig. I), up an inclined portion 18c (Fig. III) in the cam-rail. The decorated tumbler is thus raised from the stencil, and upon moving to station A, the attendant removes the tumbler and 30 installs an undecorated one in its place. Thus, the machine is adapted successively to apply decorations upon the tumblers G.

In each interval between the successive engagements of the tumblers with the stencil sheet, the endless band 1 is caused automatically to advance through such interval that a fresh or new expanse of the applied film of color material is carried into position beneath the stencil sheet. 35 The means for effecting the intermittent advances of the band consist in a system of gears, sprocket-chains, and a clutch arranged within housings 28 and 28a. Such means are fully described in our above-noted patent, and further consideration of them is deemed needless. Suffice it to say that the turn-table is rotated continuously; the installed objects G are rolled successively across the stencil sheet; and the band 1 is advanced in the intervals between the successive engagements 40 of the objects with the sheet.

Additionally, the particular mechanism for applying the decorating material upon the band is fully described in our said patent, and, in the drawings of this case, we diagrammatically illustrate such mechanism by means of a roll 43. It will be understood that, as the band is intermittently moved past the roll decorating material is applied. Above the roll 43, we provide means for spreading and smoothing the applied color material, to the end that a thin film E of uniform thickness and consistency shall be provided. Such means consist in a spreader 58, as shown in outline in Fig. II and in sectional detail in Fig. III: 45 The spreader includes a flexible strip 59 of rubber, secured in a rigid block 60; the block 60 is secured in a yoke 61 which is pivotally supported on a shaft 62 mounted in a stationary frame portion 63 of the machine; and a finger 65, articulated to the frame portion 63, at 66, bears upon the yoke 61 from above, and presses the forward edge of the flexible strip 59 against the face of the band 1. The applied color material, carried by the traveling band beneath the edge 50 of strip 59, is spread and smoothed, forming the

desired uniform and thin film. A torsion spring 64 opposes the pressure of finger 65 upon the yoke 61; a screw 67 is secured at one end in a ball-and-socket joint 68 to the frame portion 63, and passes through a portion 69 with which the finger is rigidly integrated. Rotation of the screw 67 in one direction or the other swings the finger 65 either upward or downward about center 66. Such means provide for the angular adjustment of the spreader device about shaft 62, 10 whereby the pressure of the resilient spreader strip 59 against the face of band 1 may be regulated as need be, to provide the desired spreading and smoothing of the applied color material.

The color material employed in the decoration 15 of glass-ware is a moist, thick and tacky mixture of known sort, and great difficulty has been experienced in providing means of suitable physical properties for supporting a film of such material beneath the stencil sheet. We have discovered 20 that the band 1 may be advantageously constructed of flexible or elastic material, having a smooth surface and being impervious to the moist 25 decorating material. Advantageously, we construct the band of rubber, internally reinforced by means of cotton or metal fabric 1a, as indicated in section in Fig. III. The face 1b of the rubber, which is to receive the applied color 30 material, is smooth and moisture-proof; the rubber is of substantial elasticity and desirably is a solid 35 rubber, as distinguished from sponge rubber; or, if it be a sponge rubber, it is provided with an impervious vulcanized skin. A film-carrier of this structure gives good results in service, and may be readily and thoroughly cleansed, whereby one 40 and the same band may be used in the machine when the color material is changed, to meet color specifications of different designs and decorations.

We claim as our invention:

1. Stenciling apparatus including a stencil impervious in main and pervious in pattern, means adapted to present an extended surface adjacent to the pattern area of said stencil a film of moist 45 decorating material, said means comprising a body of elastic material having a film-bearing surface impervious to said moist decorating material, means for applying said material upon such surface, means for spreading and smoothing the applied material to provide uniformity in 50 the applied film, a rotary work-carrier, said work-carrier including means yieldingly sustained for rotatably supporting a round object to be decorated, means for rotating said work-carrier whereby said object is rolled in arcuate path 55 across the pattern area of said stencil, and an arcuate cam mounted in spaced relation with respect to said stencil and adapted to engage said object-supporting means, whereby, during the rotation of said work-carrier, the supported object 60 is positively shifted against the resistance of its yielding sustaining means transversely of said arcuate path.

2. The structure of claim 1, in which said rotary work-carrier is bodily adjustable relatively to 65 said stencil, whereby the radial interval from the center of carrier rotation to the pattern area of said stencil may be regulated, as described.

3. The structure of claim 1, in which said object-supporting means consists in an arm pivotally connected to said carrier and carrying a roller for engagement with said cam, said arm supporting two object-engaging members relatively movable for introduction of an object and adapted to yield in unison in response to the 70 75

- pressure of the supported object against said stencil.
4. In stenciling apparatus including a stencil impervious in main and pervious in pattern, the combination of a rotary work-carrier, said work-carrier being adapted to roll a round object to be decorated in arcuate path across the face of the said stencil, said work-carrier being adjustable relatively to said stencil for regulating the radial interval from the center of carrier rotation to the pattern area of said stencil. 5
5. A device for supporting a round object in decorating apparatus, said device including two axially aligned members between which the object is secured, said members being relatively movable to admit of the release and introduction of objects, means for supporting said members, and yielding means adapted to admit of automatic adjustment of said supporting members in response to working pressure against the supported object. 10
6. A device for supporting an object to be decorated, said device including two object-engaging members relatively movable for the introduction and release of the work, said members being movable in unison in work-securing position in response to working pressure against the supported object. 15
7. Means for supporting an object to be decorated, said means including a rotary carrier, a radial support angularly movable on said carrier, two object-engaging members carried by said support, said members being relatively movable for the introduction and release of the work, said members being adapted to yield angularly of said radial support in response to working pressure against the supported object. 20
8. A device for supporting an object to be decorated, said device including a yoke for the support of said object, and yielding means supporting said yoke. 25
9. In stenciling apparatus including a stencil impervious in main and pervious in pattern, means adapted to present on an extended surface adjacent to the pattern area of said stencil a film of decorating material, a rotary work-carrier for advancing said object arcuately and in rolling engagement with said stencil, and a cam mounted above said stencil and adapted to engage said object-supporting means from above, whereby, during the rotation of said work-carrier, said object-supporting means are positively shifted transversely of the path of object advance. 30
10. In stenciling apparatus including a stencil impervious in main and pervious in pattern, an endless band adapted to present on an extended surface adjacent to the pattern area of said stencil a film of decorating material, and means for effecting the advance of said band; the combination of means for applying said film of decorating material upon said band, and means effective during the advance of the band for spreading and smoothing the applied film. 5
11. In stenciling apparatus including a stencil impervious in main and pervious in pattern, and a member adapted to present on an extended surface adjacent to the pattern area of said stencil a thin-uniform film of decorating material; the combination of means for applying said decorating material upon said member, means for effecting movement of such member relatively to said film-applying means, and means effective during such relative movement for spreading and 10 smoothing the applied material to provide said film. 15
12. Stenciling apparatus including a stencil impervious in main and pervious in pattern, and a member adapted to present on an extended surface adjacent to the pattern area of said stencil a film of moist decorating material, said member comprising an elastic body whose film-bearing surface is impervious to said moist material, and means for spreading a smooth film of such 20 decorating material upon said impervious surface. 25
13. Stenciling apparatus including a stencil impervious in main and pervious in pattern, and a member adapted to present on an extended surface adjacent to the pattern area of said stencil a film of moist decorating material, said member comprising a reinforced flexible body of rubber whose film-bearing surface is impervious to said moist material, and means for applying said film. 30
14. Stenciling apparatus including a stencil impervious in main and pervious in pattern, an endless, flexible band adapted to present on an extended surface adjacent to the pattern area of 35 said stencil a film of moist decorating material, said band constructed of reinforced elastic material having a surface impervious to said moist material, means for effecting travel of the band relatively to the stencil, and means for progressively applying said film. 40
